UNITED STATES PATENT OFFICE.

IRA B. WOLFE, OF DERMOTT, ARKANSAS, ASSIGNEE, BY DIRECT AND MESNE ASSIGNMENTS, OF ONE-FOURTH TO JAMES A. BENNETT, ONE-EIGHTH TO WILLIAM P. DANIELS, AND ONE-EIGHTH TO WILLIAM A. DANIELS, ALL OF DERMOTT, ARKANSAS.

WINDOW-SHADE FIXTURE.

1,138,166.

Specification of Letters Patent.

Patented May 4, 1915.

Application filed August 24, 1914. Serial No. 858,302.

To all whom it may concern:

Be it known that I, IRA B. WOLFE, a citizen of the United States, residing at Dermott, in the county of Chicot and State of Arkansas, 5 have invented certain new and useful Improvements in Window-Shade Fixtures, of which the following is a specification, reference being had to the accompanying drawings.

10 My invention relates to certain new and useful improvements in window shade fixtures and has for its object ready and effective means for raising and lowering a spring shade roller with reference to the window, 15 so that the shade may screen the light at any desired altitude of the window.

With this end in view my invention consists in the details of construction and arrangement hereinafter described and 20 claimed, and shown in the drawing.

In order that the invention may be fully understood, I will proceed to describe the same referring by numerals to the accompanying drawing in which—

25 Figure 1 is a front view of a window frame equipped with my improvements. Fig. 2 is a side elevation partly in section looking from the left of Fig. 1, and Fig. 3 is a longitudinal section of the spring roller.

30 Similar reference numerals indicate like parts in the several figures of the drawing.

1 represents an ordinary window frame to which the usual sashes are applied; 2 is a window shade suitably connected with an 35 ordinary spring roller 3; and 4 and 5 are metallic cases of the design shown in side elevation, best shown at Fig. 2, open in front, with parallel sides and an integral back, or in other words, of U-form in cross 40 section, and designed to be located upon rack bars 6, before said bars are permanently secured in place upon the window frame by screws 7. Within the upper portion of the cases 4 and 5 spur wheels 8 are journaled by

45 their hubs to the sides of the casing, the inner hub in each case having an axial rectangular recess for the purpose presently explained. Also pivoted to the sides of the casing 4, and below the spur wheel 8, is a 50 ratchet pawl 9, having two points of engagement, one with the rack bar 6, and the other with the spur wheel as clearly shown in Fig. 2. This pawl is provided with a

suitable hanging cord 10 by means of which the pawl may be released, the pawl being returned to its locking position by a suitable spring 11. Bridging the two cases 4 and 5 55 is a telescopic shaft consisting of two sections 12 and 13, the former adjustable within the latter and fixed in any desired adjustment by a screw 14. The outer end of each section is provided with a short extension 15, 60 adapted to be seated in the rectangular recesses in the hubs of the spur wheels 8. The section 12 is surrounded by a coil spring 16, one end 17 being fixed in the said section and the opposite end fixed to the side of the 65 casing 5, so that as the spur wheels are rotated by the racks 6 in the downward travel of the shaft the spring 16 will be put under torsional strain and will operate to return the roller upward when desired. This section 70 shaft is inclosed within thin metal tubes 18 and 19 longitudinally adjustable one upon the other and constitute an ornamental covering for the roller. The inside faces of the casings 4 and 5 are formed near 75 their lower extremities with bayonet slots 20 (see Fig. 2), adapted to receive the rectangular extension 21 of the ordinary shade spring roller 3. While I have shown a single spring it will be understood that when 80 a heavy or wide shade is used a double spring should be used instead of the spring 16.

Having described the construction and arrangement of the several parts, I will now 85 describe the operation. The several parts being in positions shown at Fig. 1 with the shade screening the upper part of a window, and it being desired to screen the window at a lower location, the shade and its roller 90 are pulled downwardly after the pawl 9 has been released by the cord 10; the roller 3 by reason of its connection with the cases 4 and 5, causes said cases to descend upon the rack bars 6, and by reason of the spur wheels 8 95 meshing with said bars both cases travel uniformly, and in view of the connections of the spring 16 with the telescopic shaft and the casing 5, the spring is subjected to torsion. It will be readily appreciated that the tension 100 of the spring 16 is in excess of the tension of the spring 11 coacting with the pawl 9 whereby it will be perceived that it is essential to provide said pawl with the second

point of engagement or tail 22 to coat with a rack bar 6. The tail 22 is so disposed relative to the pawl 9 proper as to afford a pawl of substantial V shape and it is to be observed that the pivotal connection of the pawl with the case or carriage 4 is at the apex of said pawl, and it is to be further observed that said pawl is positioned below the spur wheel 8. When the shade has been located as desired the cord 10 is released, whereupon the spring 11 will cause the pawl 9 to interlock with the rack 6, and also the spur wheel 8, and hence the shade will be securely held in its adjusted position. When it may be desired to raise the shade to any degree, the pawl 9, is released and the spring in returning to its normal condition will cause the telescopic shaft to rotate and the spur wheels to which it is fixed will in an obvious manner climb the rack bar and necessarily carry with them, the cases 4 and 5, to which they are journaled, and the shade roller will be raised.

Many minor changes may be made in the mere details of construction without departing from the spirit of my invention.

What I claim as new and desire to secure by Letters Patent is:

1. A shade fixture comprising, in combination, rack bars adapted to be mounted in vertical position, carriages slidably engaged with each of the rack bars, spur wheels rotatably supported by the carriages and in mesh with the rack bars, a spring roller operatively engaged with the spur wheels, said roller being adapted to be placed under tension upon movement of the carriages in one direction, a pawl pivotally supported intermediate its length by one of the carriages and having its opposite extremities adapted for engagement with the adjacent spur wheel and with the adjacent rack, and means for imparting rocking movement to the pawl whereby it may be simultaneously disengaged from the spur wheel and the rack.

2. A shade fixture comprising, in combination, rack bars adapted to be mounted in vertical position, carriages slidably engaged with each of the rack bars, spur wheels rotatably supported by the carriages and in mesh with the rack bars, a spring roller operatively engaged with the spur wheels, said roller being adapted to be placed under tension upon movement of the carriages in one

direction, a pawl pivotally supported intermediate its length by one of the carriages and having its opposite extremities adapted for engagement with the adjacent spur wheel and with the adjacent rack, means for imparting rocking movement to the pawl whereby it may be simultaneously disengaged from the spur wheel and the rack, and means for normally maintaining said pawl in engagement with the spur wheel and the rack.

3. A shade fixture comprising, in combination, rack bars adapted to be mounted in vertical position, carriages slidably engaged with each of the rack bars, spur wheels rotatably supported by the carriages and in mesh with the rack bars, a spring roller operatively engaged with the spur wheels, said roller being adapted to be placed under tension upon movement of the carriages in one direction, a pawl pivotally supported intermediate its length by one of the carriages and having its opposite extremities adapted for engagement with the adjacent spur wheel and with the adjacent rack, and means for imparting rocking movement to the pawl whereby it may be simultaneously disengaged from the spur wheel and the rack, said pawl being positioned below the spur wheel.

4. A shade fixture comprising, in combination, rack bars adapted to be mounted in vertical position, carriages slidably engaged with each of the rack bars, spur wheels rotatably supported by the carriages and in mesh with the rack bars, a spring roller operatively engaged with the spur wheels, said roller being adapted to be placed under tension upon movement of the carriages in one direction, a V-shaped pawl pivotally supported at its apex by one of the carriages below the spur wheel and having its opposite extremities adapted for engagement with the adjacent spur wheel and with the adjacent rack, and means for imparting rocking movement to the pawl whereby it may be simultaneously disengaged from the spur wheel and the rack.

In testimony whereof I hereunto affix my signature in the presence of two witnesses.

IRA B. WOLFE.
